UNITED STATES PATENT OFFICE.

ADOLPH SCHNEIDER, OF CHICAGO, ILLINOIS, ASSIGNOR TO HENRY SCHNEIDER, OF TRINIDAD, COLORADO.

REGULATOR FOR USE WITH FILLING-VALVES.

No. 846,352.

Specification of Letters Patent.

Patented March 5, 1907.

Application filed September 14, 1905. Serial No. 278,482.

To all whom it may concern:

Be it known that I, ADOLPH SCHNEIDER, a citizen of the United States, residing at Chicago, in the county of Cook and State of Illinois, have invented certain new and useful Improvements in Regulators for Use with Filling-Valves, of which the following is a specification.

This invention is intended and adapted to be used with valves of the general character described in Letters Patent No. 728,307 and other patents to the same inventor, in which the valve is provided with liquid and air equalization passages, so that the pressure in the bottle and the tank will be equalized before the liquid begins to flow. In valves of the character indicated it sometimes happens that the liquid-passages will be slightly opened before complete equalization takes place, in which case the liquid will be sucked into the bottle by reason of the greater pressure in the tank, which causes foaming and prevents the bottle from being completely and perfectly filled.

The object of the present invention is to overcome this difficulty by providing a regulator which will prevent the discharge of any liquid whatever into the bottle before equalization and is intended entirely as an attachment to the valve and not as a substitute therefor, so that when the valve is operated perfectly the regulator will remain inactive, but will serve as a safeguard to insure the proper operation of the valve at all times.

The invention consists in the features of construction and combination of parts hereinafter described and claimed.

In the drawings, Figure 1 is a sectional view of a valve of the character indicated, showing the regulator in place; Fig. 2, a side elevation of the valve, showing a slightly-modified form of regulator in section; Fig. 3, a cross-sectional view of the regulator of Figs. 1 and 2, and Figs. 4 and 5 views showing slightly-modified forms of regulator.

The regulator which more especially forms the subject-matter of the present invention consists of an inverted-U-shaped tubular casing 1, having at its attaching end screw-threads 2 or other suitable attaching means and having in its body a continuous passage 3, terminating at its outer end in an enlarged chamber 4, leaving a tapered shoulder 5, which serves as a valve-seat. The enlarged

chamber opens downwardly at its outer end 55 at a point in close proximity to the bottom wall 6 of a liquid-supply tank of the usual character. Within the enlarged end chamber is a movable valve member 7, adapted to move up and down within the enlarged chamber and provided with ribs or flanges 8, which contact the walls of the chamber, leaving spaces 9 for the passage of liquid up around the valve member. The valve member is tapered at its inner end 10 and adapted 60 to seat against the beveled shoulder 5 when in raised position and when unseated rests upon a cross-pin 11, as shown in Fig. 1. In Fig. 2 the movable member 12 is constructed of a sufficient length to project out of the 70 chamber and rest when unseated upon the walls 6 of the tank, the cross-pin being dispensed with. In Fig. 4 is shown a slightly-modified form of construction, in which a tubular casing 13 is employed provided with 75 attaching screw-threads 14 and having a passage 15, terminating in a chamber 16, similar to that hitherto described, and above the chamber 16 is a bore 17, leaving a shoulder 18 for the contact of a coiled spring 19, which 80 is adapted to bear down against a valve member 20. The valve member in this instance is provided with an upwardly-projecting stud 21, around which the spring is coiled, and normally rests upon a cross-pin 22, being held thereon by the tension of the spring. It will be understood that in the construction of Fig. 4 the spring serves to exert an 85 additional tension upon the valve member, so that it will require a greater amount of 90 pressure to seat the member against the beveled shoulder. In Fig. 5 the valve member 7^a is ball-shaped; but the casing is similar to that of Fig. 1.

The regulator is screw-threaded or otherwise secured to a neck 23, which forms part of a valve-casing 24, and within the valve-casing is a beveled valve-plug 25, held in place by means of caps 26 at the ends of a valve-casing. The casing is provided with a 95 liquid-supply passage 27, connecting with liquid-passage 28 in the valve-plug, and said passage leads to and communicates with the filling-tube 29, which passes through a filling-head 30, having a neck 31 screw-threaded into the valve-plug. Within the 100 liquid-supply pipe is an air-passage 32, opening at its upper end into an annular chamber 105

- 33, which communicates by means of air-passages 34 and 35 with an air-pipe 36, the valve being in all essential features the same as that described in the prior patent referred to, and the passages 34 and 35 are preferably arranged so that said passages will come into communication with one another prior to the alinement of the liquid-supply passages, thereby enabling a preliminary equalization of pressure. It will be understood, however, that the invention is not limited to use with valves of the precise character herein described, since it is adapted for use with any pressure-equalization valve.
- 15 5 In use the valve member in the regulator will normally remain seated, so that when the liquid flows down by gravity after the pressure has been equalized the regulator will remain in normal position. If, however, the pressure should be imperfectly equalized in the bottle prior to the admission of liquid, said liquid will begin to rush through the regulator, and said unusual rush of liquid will serve to force up the valve member
- 20 10 within the regulator and seat the same, thereby cutting off the flow of liquid until the pressure has been properly equalized, at which point, there being no suction from the bottle and no abnormal flow of liquid through
- 25 15 the regulator, the valve member therein will drop to normal position, allowing the liquid to flow unimpeded through the regulator and valve into the bottle. If the action of the regulator of either Figs. 1, 2, and 5 be too
- 30 20 free and the valve member too easily seated, the regulator of Fig. 4 may be substituted, which is provided with a coil-spring, which prevents the easy seating of the valve. In
- 35 25 other respects the operation of the two is
- 40 30 entirely the same.
- It will be seen from the foregoing description that the regulator of the present invention can be easily and quickly attached to valves of the character indicated and when
- 45 35 so attached will serve to regulate and control the operation of said valves and prevent the possibility of imperfect action. Another feature of importance lies in the fact that the regulator serves to prevent any sudden in-
- 50 40 rush of liquid, which, if violent, sometimes breaks the bottle, thereby resulting in injury to the attendant and waste of the liquid.
- What I claim as new, and desire to secure by Letters Patent, is—
- 55 45 1. In combination with a pressure-equalization valve, a regulator having an imperfo-

rate valve member normally unseated and adapted to be seated by an abnormal rush of liquid through the valve to tightly seal the opening, substantially as described. 60

2. In combination with a pressure-equalization valve, a regulator consisting of a tubular casing, and a movable imperforate valve member in one end of the casing adapted to be seated by an abnormal rush of liquid 65 through the regulator and equalization-valve to tightly seal the opening, substantially as described.

3. In combination with a pressure-equalization valve, a regulator having a tubular 70 casing of inverted-U shape having one end inserted into the liquid-passage of the equalization-valve and the other end downwardly opening and formed with an enlarged chamber providing a seat, a movable imperforate 75 valve member normally open and adapted to be seated by an abnormal rush of pressure through the regulator and equalization-valve to tightly seal the opening, substantially as described. 80

4. In combination with a pressure-equalization valve, a regulator consisting of a tubular casing of inverted-U shape having one end inserted into the liquid-supply passage of the equalization-valve and the other end 85 opening downwardly and provided with an enlarged valve-chamber beveled at its inner end to form a seat, and an imperforate valve member slidably mounted within the chamber and provided with ribs or flanges around 90 its outer wall and adapted to be seated by an abnormal rush of liquid through the regulator and equalization-valve to tightly seal the opening, substantially as described. 95

5. In combination with a pressure-equalization valve a regulator having a tubular casing of inverted-U shape having one end inserted into the liquid-passage of the equalization-valve and the other end downwardly opening and formed with an enlarged chamber providing a seat, a movable imperforate 100 valve member normally open and adapted to be seated by an abnormal rush of pressure through the regulator and equalization-valve to tightly seal the opening, and a 105 spring for normally holding the valve unseated, substantially as described.

ADOLPH SCHNEIDER.
